FULL-FASHIONED STOCKING

Hans Thierfelder and Ernst Dietz, Auerbach i.
Erzg., GermanyApplication July 9, 1938, Serial No. 218,352
In Germany March 19, 1938

5 Claims. (Cl. 66—178)

This invention relates to full-fashioned stockings.

In the known kinds of stockings narrowing of the leg for shaping the stocking involves the production of fashioning points which extend over a relatively short portion of the leg. This is due to the fact that narrowing of the fabric must always be to the extent of two needles on each side. Consequently, the total amount of narrowing required can be effected with a relatively small number of fashioning points which must always be arranged at a moderate uniform distance from one another, and the narrowing of the stocking is thus restricted to a short piece of the leg. Uneven spacing of the fashioning points within the narrowing zone of the leg has been avoided for the sake of a uniform appearance of the zone located between the fashioning points and the seam. A stocking, however, made in this way is not in fact fully fashioned and when worn has various disadvantages. In particular, unsightly creases form easily in the region of the ankle or the courses are stretched too much in this region; so that this part of the stocking is shinier than the adjacent parts and the goods have a defective look.

It is the object of the present invention to distribute the fashioning points in such manner that a perfect fit for all shapes of leg is insured. For this purpose, the fashioning points are arranged at varying distances from one another according to the shape of the stocking desired, but in spite of this the uniform appearance of the zone lying between the line of fashioning points and the seam is maintained. Furthermore, the invention takes into consideration that in the courses to be narrowed the loops must always be transferred two needles at the edge of the fabric, since near the boundary loop of the selvage there must always be a jack sinker and not a dividing sinker if a perfect selvage is to be formed.

These objects are attained according to the invention primarily by providing a line composed not only of narrowing fashioning points but also of additional fashioning loops, the courses of additional mock fashioning loops, the courses containing the latter being so worked that the width of the fabric is not reduced. The fashioning points may thus be arranged in one or more lines on each side of the stocking and some or all of the narrowing fashioning points may be placed in the seam. The spacing of the individual fashioning points from one another may be chosen as desired without the appear-

ance of the stocking being thereby detrimentally affected.

The invention is illustrated by way of example in the accompanying drawings, in which

Fig. 1 is a side view of a stocking made in accordance with the invention;

Figures 2 and 3 are detail views explaining the formation of the various fashioning loops, the portions of courses transferred two gauges being indicated by horizontal lines; the loops transferred only one gauge by points; and the loops not transferred in the rows of fashioning loops by small circles; and

Fig. 4 is a side view of another stocking made according to the invention;

Figs. 5 to 8 illustrate methods of narrowing and forming fashioning points.

Figure 9 is a diagram illustrating a method of forming full fashioned stockings having actual and mock fashioning points.

The stocking can be made in any desired manner, and the fashioning points may all be positioned on a dot and dash line 2 as shown in Fig. 1 or distributed over several lines or partly placed in the back seam of the stocking.

In order to be able to insert between the actual fashioning points additional mock fashioning points, i. e. those where there is no narrowing of the fabric, the course portions 3 shown in Fig. 30 and Fig. 5 can be transferred two needles. In this case, however, in those courses 28 (Fig. 5) in which narrowing is not to occur in spite of the transfer of a more or less large group 4 of loops to the extent of two needles, there must be several loops at the edge which are not transferred. Only one or two of these border loops 5, which are directly adjacent to the course portion 4 transferred two needles, are then transferred one needle by an additional narrowing operation so as partly to close the hole produced by the first transfer. In order to obtain a satisfactory selvage, however, the border loop 5 and, if desired, one or more adjacent loops are not transferred.

Instead of proceeding in the manner described, it is possible also to attain the object of the invention in the manner indicated in Fig. 3 and Fig. 6. In this case the course portions 1 or 8 between the selvage and the line of fashioning loops, except for a few border loops 9, are transferred one needle in all courses in which fashioning points are to be present, and then the border loops 16 in these courses in which narrowing is desired are transferred two needles by a special narrowing operation. This method is

applied in the manufacture of very fine and thin stockings and in any case where the fashioning points are not to become as conspicuous as after a transfer by two needles, the loops which have been transferred two needles being hidden in the seam.

The object of the invention can also be attained when, in a course where no narrowing is to be effected, a course portion 21 (Fig. 7) extending from the line of fashioning points towards but not to the selvage is transferred one needle, so that at a distance from the selvage and the seam to be formed there perforations having an open work effect appear and may be arranged so as to look like a pattern line. In the narrowed courses, on the other hand, the entire portion between the line of fashioning points and the selvage is transferred two needles, whereupon, if desired, a single loop may be subsequently transferred still another needle to one side or the other in the open work line, to produce at that point an opening which forms a pattern with the other openings.

Instead of transferring one needle all except a few loops at the selvage of the portions lying between the selvage and the line of fashioning points and then transferring these loops two needles in those courses 23 (Fig. 8) where there is to be actual narrowing, all of the portions in question could first be transferred one needle and the selvage loops in the courses to be narrowed then transferred an additional needle.

The double transfer of loops required for forming a good selvage need not necessarily occur in one and the same course but may be effected in two consecutive courses, the transfer in each being to the extent of one needle only. It is necessary, however, so to arrange the two narrowing operations required for a fashioning point that the first occurs in a course in which the carrier lays the thread from the selvage to which the fashioning point belongs in the direction of the other selvage and that the second occurs in a course in which the carrier returns again to the selvage nearest which the fashioning point is to be formed. In this way actual and mock fashioning points are produced (shown in Figures 3 and 7 respectively) which differ from each other only in that the thread in the courses to be narrowed is laid in the usual way on fewer needles than before, whereas in the courses which are to have mock fashioning points the thread is laid upon just as many needles as in the preceding course.

Whenever two fashioning points appear in one course on the same side of the stocking, it is advisable to place one of them in the seam. In the same way, single fashioning points may be disposed in the seam if at certain points of a fine-meshed stocking greater narrowing is desirable than can be attained by the chosen spacing of the fashioning points in their line. For other reasons too some or all fashioning points may be disposed in the seam and accordingly the visible line of fashioning points preferably includes only mock points.

By interposing mock fashioning points between actual fashioning points these points can be made to form a line of any length without appearing too scattered and giving the impression of a faulty piece of work.

Actual and mock fashioning points may alternate at will in the line, and, in particular, the number of mock points arranged between two narrowed courses may vary within wide limits,

e. g. between none and twelve. Figure 9 illustrates a method of forming a full fashioned stocking wherein both kinds of points, namely, actual and mock fashioning points, are made by transferring one needle a group of loops at the selvage in two successive courses and placing the thread in the courses having actual fashioning points over one frame needle less than in the preceding course, while the path of the carrier is left unchanged in courses having mock fashioning points. At points where a portion of the leg is to be exceptionally narrowed there are only a few mock fashioning points or none at all, while at the upper and lower end of the leg narrowing more mock than actual fashioning points are required. In practice, the number of fashioning points interposed between any two narrowed courses is generally first reduced from top to bottom according to a predetermined plan and the shape desired and then increased again.

For the reason stated, the line of fashioning points 2 is preferably continued downwardly below the region of narrowing of the calf of the leg and may terminate at the upper end of the high heel 11 or be continued in the latter, particularly in the front boundary line 12 thereof. A line of fashioning points of this kind, besides imparting to the stocking a better fit especially in the region of the ankle and preventing the formation of creases, affords the additional advantage that the downward extension of the line makes the leg of the wearer of the stocking appear slender. For this same purpose the upper end 15 of the line 2 may be curved away from the seam 16 of the stocking by gradually shortening, from the top of the line, the length of the course portions. The zone between the line 2 and the seam 16 can be spliced like the high heel to any extent. It may, moreover, consist of different material from that of the rest of the leg and be connected to the adjoining portion of the fabric by means of a split seam.

In order to insure a good fit of the stocking it is advantageous to widen the fabric in the region of the lower portion of the high heel, thus rendering it narrower around the ankle than in the region of the angle of the heel.

When the actual fashioning points are placed in the seam, the mock loops or points may be replaced by a tuck pattern, embroidery stitches, or by printing colored dots on the finished goods. A similar effect can be produced by the boundary line of a reinforced zone of varying width provided along the seam of the stocking.

It is possible to go still farther in the production of a perfectly shaped stocking by not only varying the spacing of the actual fashioning loops along the narrowing of the calf, for instance by making it greater near the top and bottom of the calf than in the middle, but also by positioning the line of these loops at the boundary of the sural muscles, so that the upper portion of the line is on the side of the stocking, as shown in Fig. 4, and its lower portion approaches more or less the back seam. In the example shown the line of fashioning loops has a graceful wavy form, though it can also be rectilinear, and the two lines extending on either side of the back seam may converge downwardly, so that their lower ends meet in the back seam.

The fashioning points in other parts of the stocking, particularly in the thigh according to Fig. 4, may be arranged and formed similarly to those in the calf portion. Furthermore, the

fashioning points in any part of the stocking need not be disposed so as to form an uninterrupted line, but the latter may be interrupted at will.

We claim:

1. The method of forming a full-fashioned stocking having actual and mock fashioning points, which comprises transferring two needles that portion of each course to be narrowed lying between the selvage and the actual fashioning point and the corresponding portion of every other course which is to have a mock fashioning point except for a few loops at the selvage, and then in every such other course transferring one needle in the direction of the previous transfer some of the previously untransferred loops which are adjacent to the previously transferred portion.

2. The method of forming a full-fashioned stocking having actual and mock fashioning points, which comprises transferring one needle all the loops of the courses to be narrowed and of those to receive mock fashioning points between the actual fashioning points and the selvage, except for a few loops at the selvage, in the direction of the line to be formed of fashioning points and then transferring two needles the edge loops of the courses to be narrowed in the same direction.

3. The method of forming a full-fashioned stocking having actual and mock fashioning points, which comprises producing both kinds of points by transferring one needle a group of

loops at the selvage in two successive courses, placing in the courses having actual fashioning points the thread always over one frame needle less than in the preceding course and leaving in the courses having mock fashioning points the path of the carrier unchanged.

4. A full-fashioned stocking having a back seam and a line of fashioning points, said line having a lower portion extending substantially parallel to and at a distance from said back seam and an upper portion extending away from said back seam and at a greater distance therefrom than the lower portion, said line consisting of actual fashioning points as well as mock fashioning points, the courses containing the latter being worked so as not to reduce the width of the fabric.

5. A full-fashioned stocking having a back seam and a line of fashioning points, said line having a lower portion extending substantially parallel to and at a distance from said back seam and an upper portion extending away from said back seam and at a greater distance therefrom than the lower portion, said line consisting of actual fashioning points and mock fashioning points interposed between said actual fashioning points, the number of the mock fashioning points interposed between the actual fashioning points varying along the extent of said line of fashioning points.
